UNITED STATES PATENT OFFICE.

CORNELIUS KURZ, OF CLEVELAND, OHIO.

TOILET-CABINET FOR INFANTS.

SPECIFICATION forming part of Letters Patent No. 439,666, dated November 4, 1890.

Application filed May 22, 1890. Serial No. 352,802. (No model.)

To all whom it may concern:

Be it known that I, CORNELIUS KURZ, a citizen of the United States, residing at Cleveland, in the county of Cuyahoga and State of Ohio, have invented certain new and useful Improvements in Toilet-Cabinets for Infants; and I do declare the following to be a full, clear, and exact description of the invention, such as will enable others skilled in the art to 10 which it appertains to make and use the same, reference being had to the accompanying drawings, and to the letters of reference marked thereon, which form a part of this specification.

15 My invention relates to improvements in toilet-cabinet for infants; and it consists in certain features of construction, which will be fully set forth in the following specification.

In the drawings, Figure 1 is a perspective view of my improved toilet-cabinet for infants. Fig. 2 is a front elevation, with the cover and doors open, a portion immediately in front of the bath-tub being broken away. Fig. 3 is a plan of my improved cabinet with the cover open. Fig. 4 is a side elevation, with one corner broken away and the cover also open.

The object of my invention is to produce a suitable device to wash and dress infants in 20 a convenient, easy, and practical manner, and to have all necessary facilities and auxiliaries for the occasion in a convenient and compact form, and at the same time arranged in an appropriate receptacle, which will present a 25 pleasing and ornamental appearance as a piece of furniture in a room or parlor. This I accomplish by means of an infant's cabinet containing a bath-tub, suitable drawers, and receptacles for toilet articles, and which 30 consists in a cabinet A, provided with doors A', cover A², and drawers B. Cover A² is hinged at a'. The back or projecting portion a² is secured to the cover and turns back with said cover when opened, as shown at Figs. 3 and 4. 35 On the opposite ends of the cover A² are guard rods or rails a to prevent the infant from working or falling off said cover. On the top of said cover A² is an oblong cushion C, which is secured by means of straps c c to prevent 40 its falling off when the lid or cover is turned back, as shown at Figs. 3 and 4. This cover is also provided with a closing-spring K, which

will be hereinafter fully described in connection with its appropriate working mechanism. On the inside of the cabinet are drawers 55 B' B', which are not shown when said doors A' are closed.

The bath-tub D is of the ordinary construction and provided with a flange d, encircling its entire periphery, preferably made of an angle-iron and soldered or riveted to said tub. The tub is provided with handles d' for removing said tub when occasion demands. A vent-hole d² (with a plug) is provided to allow the water to run into a tub E, located immediately beneath said tub D. The bath-tub is suspended on a shelf A³ by means of an opening in said shelf and projecting below the same, as shown. The flange d aforesaid rests upon a rubber gasket F, which surrounds 7c the opening in said shelf A³, thus preventing any water that may be thrown over the edge of the bath-tub from leaking to the compartments or drawers under the same. Immediately surrounding said bath-tub are small 75 compartments g g, &c., for containing all necessary articles pertaining to the toilet of an infant. It is obvious that all of these compartments can be modified to suit the varied fancies of purchasers. On the extreme right-hand end of said toilet-cabinet A is a partition A⁴, which forms a narrow opening or pocket A⁵. This opening is for the reception of a quadrant H, one end being hinged to cover A², and its opposite end being free and terminating in a lip h for engaging a spring-catch I when said cover A² is open. Secured to the opposite end of spring-catch I is a wire or chain i, which is attached to a treadle J, located under the cabinet, as shown at Fig. 4. 90

The spring K, previously referred to for operating cover A², is of peculiar and novel construction. It consists of a single piece of wire with its opposite ends coiled at k and bent in form of a loop k', forming two members. The lower ends of the wire terminate in straight portions, which are screw-threaded for receiving nuts k². Secured to the cover A² is a yoke L, which supports or receives the pressure of spring K, this pressure of the 95 spring being in the direction to close the cover aforesaid. The cover is secured by a catch a⁵, and is further provided with buffers a⁶, which can be made of rubber or spiral springs. To 100

prevent the buffers a^6 from bruising cover A^2 , I provide buttons of flat rubber or thick felt a^7 , which also answer the purpose of closing the cover without noise, which would shock or 5 frighten the infant.

In operating my improved cabinet I detach the catch on the cover and raise said cover until the quadrant H slips over and engages spring-catch I . After the infant has been 10 properly bathed or washed I put my foot upon treadle J , when a slight pressure disengages said spring-catch I and the resilience of the spring K closes said cover A^2 , when the infant is put upon the cushion C and manipulated 15 until ready to be dressed, and it can be dressed when reclining on said cushion C , previously referred to.

It is not necessary to have the quadrant for supporting said cover, as any suitable device 20 will answer the purpose without detracting from the spirit of my invention, and the same may be said of the spring-catch, previously referred to, as any suitable automatic catch will answer the purpose. The contour of the 25 bath-tub and the position or location of the tub E and various drawers can also be ar-

ranged differently without departing from the spirit of my invention.

That which I consider as new, and desire to secure by Letters Patent, is—

1. In an infant's toilet-cabinet, the combination, substantially as shown, of a bath-tub supported by a flange resting upon a shelf and a rubber gasket or suitable packing material interposed between said flange and 35 shelf, a waste-water tub immediately under said bath-tub, and toilet-compartments surrounding said bath-tub, as shown and described.

2. In combination with an infant's toilet- 40 cabinet having a bath-tub located therein and provided with a suitable spring - actuating cover, operated by foot mechanism for releasing a quadrant and allowing said cover to close and rest upon buffers, as shown and specified. 45

In testimony whereof I affix my signature in presence of two witnesses.

CORNELIUS KURZ.
